UNITED STATES PATENT OFFICE.

GEORGE ALBERT LEY, OF CHICAGO, ILLINOIS.

FLASH-LIGHT BAG.

1,350,730.

Specification of Letters Patent. Patented Aug. 24, 1920.

Application filed March 11, 1918, Serial No. 221,822. Renewed July 13, 1920. Serial No. 395,994.

To all whom it may concern:

Be it known that I, GEORGE A. LEY, a citizen of the United States, and a resident of Chicago, in the county of Cook and State of Illinois, have invented a new and useful Improvement in Flash-Light Bags, of which the following is a specification.

My invention relates to improvements in flashlight bags, and it consists in the constructions, combinations and arrangements herein described and claimed.

An object of my invention is to provide a flashlight bag including as one of the important features, a connecting link between the lower end of the shank and the staff, adapted to be moved past the dead center and automatically hold the bag in the open position.

Another object of the invention is to provide a flashlight bag including a supporting staff running from the crown of the bag to the lower ends of the bottom ribs inside of the bag, thereby keeping the flash which is created in the flash pan supported on the staff, a safe distance from the bag.

Another object of the invention is to provide a solid and reversible bag coupling by means of which the bag may be supported in either one of two positions and the change in the positions may be quickly made.

Another object of the invention is to provide a flashlight bag having novel means for emptying the smoke, said means including a flap normally covering a smoke opening at the bottom, the flap falling back automatically to uncover the opening when the bag is turned over.

Another object of the invention resides in an improved form of the flash pan and support therefor.

Other objects and advantages will appear in the following specification, reference being had to the accompanying drawings in which:

Fig. 1 is a perspective view of the flashlight bag in the elevated position.

Fig. 2 is a perspective view of the flashlight bag in the lower position.

Fig. 3 is a detail perspective view showing a portion of the frame work.

Fig. 4 is a detail perspective view of the reversible bag coupling.

Fig. 5 is a perspective view of the flashlight bag frame.

Fig. 6 is a perspective view showing the position of the connecting links.

Fig. 7 is an enlarged section on the line 7—7 of Fig. 2.

Fig. 8 is a rear elevation of the flash pan holder showing the pan in place. 60

Fig. 9 is a horizontal section on the line 9—9 of Fig. 8; and

Fig. 10 is a cross section on the line 10—10 of Fig. 9.

The herein disclosed invention is primarily an improvement on my Patent No. 1,198,361, granted Sept. 12, 1916, and embodies certain refinements developed in the use of the flashlight bag. Certain features will be recognized to be substantially the same in the construction of the flashlight bag in both cases, but the description of the improved bag will be proceeded with from the beginning. 65 70 75

Referring now to Figs. 1 and 5, it will be observed that the hood 1 consisting of an opaque fabric, rubberized white on the inside to provide an efficient reflecting surface, is stretched over the ribs 2 which support the bag. The ends of the ribs 2 are 80 bounded by a cord or wire 3, and a translucent screen of white fire-proof fabric is stretched over the wire or cord and closes the front end of the bag.

The bag is adapted to hold the smoke of 85 several charges or flashes, and the smoke is discharged through an opening 4 near the bottom of the bag when the bag is turned upside down. The opening 4 is closed by a flap 5 which is sewed in place at 6 at the top, 90 and the flap normally closes the opening 4 when the bag is in the upright position illustrated in Figs. 1 and 2. When the bag is turned over to release the smoke, the flap 5 automatically falls back and uncovers the 95 opening.

Running from a point in alignment with the lower ends of the bottom ribs to the crown of the bag, is a staff 7. The staff 7 is made in two parts and constructed of square 100 tubing. There are several purposes in making the staff in this manner. One of the purposes is to provide a means for connecting the flash pan holder 8 in place in the middle of the staff. The flash pan holder 105 will be described in detail later on. Another purpose is, to effect an attachment of the bag on the supporting standard through the medium of a reversible coupling.

Turning of the staff and consequently the 110 rocking of the flashlight bag, is prevented by the square staff and the square connec-

tions thereto. The reversible coupling just referred to, is a metallic bar bent in the middle and the respective portions disposed at angles with respect to each other. The 5 upper portion of the reversible coupling is square as at 9 and fits into the square tubing of the staff 7.

The lower portion of the reversible coupling is round as at 10, and this portion fits 10 into one of a plurality of telescopic members 11 which constitute the standard upon which the flashlight bag is supported. The respective members are held in position by clamp screws 12 which are clearly illustrated 15 in Fig. 3. A shoulder 13 in the middle of the reversible coupling, serves as an abutment for the staff when fitted into place.

By turning the reversible coupling in either 20 one or the other of two positions with respect to the flashlight bag, the flashlight bag is capable of assuming either of the positions indicated in Figs. 1 and 2. When the flashlight bag is disposed at either of these 25 positions, it is in the proper position on the standard to direct the light of the flash on the subject. In this connection it should be observed that the upper clamp screw 12 does not bear against the round shank 10 of the reversible coupling, but rather on one of the 30 telescopic members of the standard in which the reversible coupling is revolvably mounted by reason of the round shank 10. In order to keep the shank 10 from turning in the standard, the upper tube of the standard has 35 a pin 11^a over which a slot 10^a in the shank 10 fits. The shank 10 is made of square tubing in the event that the members of the standard are also square.

The upper end of the staff 7 is pivoted to 40 a slidable collar 14 on a shank 16 located at the crown of the bag. The upper ends of the ribs 2 are secured to a wire 15 applied and fastened in a peripheral groove in the slidable collar. The wire 15 forms the pivot 45 for the ribs, the ends of which work in slots cut in from the edge of the collar. In this respect, the mounting of the ribs is very much like that of the ordinary umbrella ribs.

50 Braces 17 are pivotally secured at one end to a brace collar 18 secured on the lower end of the shank 16. The brace collar 18 is arranged similarly to the slidable collar 15, in that it has a peripheral groove for receiving 55 a pivot wire, and slots cut in from the edge to receive or accommodate the ends of the braces 17. The outer ends of the braces 17 are pivoted in clips in turn secured to the respective ribs, as shown in Fig. 5.

60 A connecting link 19 works between the brace collar 18 and the staff 7. The connecting link 19 holds the hood in the open position. The connecting link is pivotally mounted in the ears of a clip 20 secured to 65 the staff 7. The other end of the link is

pivotal secured to the same wire to which the braces 17 are fastened on the brace collar 18. The latter end of the connecting link 19 is moved past the dead center in opening the bag, and thus forms a brace for holding 70 the bag open so that there can be no danger of the bag suddenly collapsing at a critical moment.

Wired to the grooved sleeve of the collars 15 and 18 is a fabric cover 21 which envelops 75 the shank 16. The fabric cover 21 prevents corrosion of the shank 16 by the smoke in the bag. The cover 21 collapses when the collars 15 and 18 are moved together in closing the bag, and stretches to cover the shank 80 as shown in Fig. 5, when the bag is opened. Incidentally it will be observed in Fig. 6, that the shank 16 is made in two parts, screwed together, so that the shank may be taken apart in packing the bag for shipment. 85

A knob 22 is secured on top of the shank 16, and a finger grip 23 is formed on the slidable collar 14. The flashlight bag is opened and closed by means of the button 22 and the finger grip 23, both being exposed 90 on the outside, as clearly shown in Figs. 1 and 2.

Formed in the back of the bag is a recess 24 through which access to the flash pan holder 8, previously referred to, is had. 95 The recess 24 is in the nature of a hand hole into which the operator reaches to insert the flash pans and make any necessary adjustments. Consider Fig. 7. Here it will be seen that the flash pan holder 8 has a 100 peripheral groove 25 in which the cloth of the flash bag and more particularly that portion of the cloth forming the recess 24, is secured.

The flash pan holder 8 has a central opening 26 through which the flash pan 27 is inserted. The flash pan has a knob by which it is handled. The back of the flash pan 27 is longer than the opening 26 and the extended portions of the flash pan 27 110 indicated 28 in Fig. 9, rest in recesses 29 formed adjacent to the lateral extremities of the opening 26.

Secured to the flash pan holder 8 and covering a portion of the opening 26, is a pan 115 retaining plate 30, the upper edge of which abuts the lower portion of the flash pan 27 as clearly shown in Figs. 7 and 8. The retaining plate 30 is secured in position by the bolt 31 of binding screws 32, which are insulated from the metallic portions of the flash pan holder 8 and the plate 30, by the insulating sleeves 33. The bolt 31 connects with contact plates 34 which are also insulated from the metallic flash pan holder 8, 120 and are adapted to engage the contact 35 carried by the flash pan 27.

Pressing against the knob of the flash pan 27, is a trap door 36. The trap door is adapted to close the opening 26 when there 130

is no flash pan in position. The trap door has a knob by means of which it is opened. A spring 37 is included in the hinge 38 of the trap door, and tends to normally close 5 the trap door. The tension of the spring 37 also causes the trap door to bear against the flash pan 27 and keep it in position.

Secured in the bottom portion of the flash pan holder 8, is a pair of binding posts 39 10 which are insulated from the holder 8 and are in common electrical connection with a pole piece 40 on the back. The various binding posts 32 and 39 are employed in completing the electric circuit connections 15 to the spring fingers 41 of the flash pan 27. The fingers 41 bear against a fuse 42 which is visible through the opening 43 in the bottom of the flash pan, and ignites the flash powder on the heating of the fuse 42.

20 Consider Fig. 8. Here the circuit connections are illustrated. If it be desired to simply fire one flash pan, the wires 44 and 45 are connected in series with the spring fingers 41 through the binding posts 32. If it 25 be desired to fire a number of flash bags, the wires are connected as indicated in dotted lines. This is also a series connection, it having been found in practice, that the charges are fired better by connecting the 30 pans in series as illustrated.

This feature leads to the consideration of an important point in the arrangement of the flash pan and holder. It will be observed that the flash pan 27 has no wire 35 connections whatever. The wire connections are made solely to the flash pan as clearly illustrated in Fig. 8. Obviously the advantage of this arrangement is, that the flash pan may be readily inserted in position 40 where it is held by the spring pressed trap door 36, and the annoyance of connecting and disconnecting wires to make the proper connections, is entirely overcome.

By the arrangement just described and 45 illustrated in Fig. 8, as many units may be added as may be found necessary, as in photographing large groups, banquets, factories, etc. This arrangement also embodies another improvement in that several of the 50 flash pans with the fuses, may be tested one after the other by simply placing the bottom of the flash pan against the two terminals or binding posts 32, it being unnecessary to detach any of the wires to do this. 55 Also, it is unnecessary to put the flash pan in the bag first before the test can be made. The ability to test the flash pan from the outside, is an advantage of no little importance, in that it makes for speed, which is 60 often essential in work of this kind.

Projecting in opposite directions from the upper and lower edges of the flash pan holder 8, are square stems 46 which are slipped into the ends of the square staff 7. 65 The connection between the stems 46 and the

staff member is tight enough to hold the parts together under normal conditions. These parts may readily be taken apart when it is desired to pack the flash bag for storage or for transportation.

70

A proof light 47 is removably mounted on a plug 48 secured on the lower staff member with electrical connections to the plug 49. The testing apparatus designated 50 and mounted on the standard 11 as shown in Figs. 75 1 and 2, coöperates with the flash pan 27 in testing the fuse 42 before the flash powder is fired. This testing apparatus, however, does not enter directly in coöperation with the structural features of the flashlight bag in 80 the present instance, and for this reason, needs no further consideration.

The operation of the flashlight bag is thought to be fully understood from the foregoing description, a brief review thereof including the various advantages, may however be of value. The flashlight bag is opened by pulling the finger grip 23 on the slideable collar 14, toward the button 22 of the shank 16. This has the effect of 85 pushing the brace collar 18 away from the slideable collar 14, in which action the hood is opened. The connecting link 19 will presently move past the dead center of its pivotal mounting in the clip 20 on the staff 90 7, and when the end of the connecting link 19, that is to say the end attached to the brace collar 18, moves below the dead center, the hood is automatically held open by the links 19 which then act as a brace.

100

It is essential that the connecting links 19 be embodied in the hood. When the hood is once opened in readiness for use, it must remain so and there must be no danger of the hood collapsing. The connecting link 105 19 absolutely overcomes any tendency of the hood to collapsing.

A number of charges of flash power may be fired in the same bag before it becomes necessary to empty the bag. The smoke 110 cannot ordinarily escape because the front of the hood is closed by the translucent screen hereinbefore referred to. The smoke is adapted to escape through an opening 4 near the bottom of the bag. This opening 115 is normally closed by a flap 5 which is sewn across the opening at the top, and of course lies across the opening to close it. When the bag is turned over, the flap 4 automatically falls back, uncovering the opening so 120 that the smoke may escape.

Different positions of the flashlight bag are obtained by means of the reversible coupling illustrated in Fig. 4. This coupling may be turned around in two positions to 125 obtain the adjustments of the bag illustrated in Figs. 1 and 2. The slideable collar 14 is prevented from sticking on the shank 16 by means of the cover 21 secured to the collar 18 and to the collar 14.

130

While the construction and arrangement of the flashlight bag and its coöperating parts, is that of a generally preferred form, obviously, modifications and changes may be made without departing from the spirit of the invention, or the scope of the claims.

I claim:

1. In a flashlight bag, a hood supporting staff, a shank, a collar slidable on the shank and having a pivotal connection to the staff, ribs radiating from the slidable collar, a brace collar affixed to the lower end of the shank, braces radiating from said collar and pivotally connected to the respective ones of the ribs, and a connecting link pivotally secured between the brace collar and the staff, adapted to be moved past the dead center when the hood is opened, to retain the hood in the open position.
2. In a flashlight bag, the combination of the supporting staff, a shank, a member slid-able on the shank and having a pivotal connection to the end of the staff, ribs pivotally secured to the slidable member, a brace col-lar affixed to the end of the shank, braces pivotally secured to the brace collar and the respective ones of the ribs, means for moving the slidable collar on the shank, and means disposed between the shank and the staff, adapted to hold the flashlight bag open when moved to the open position.
3. A flashlight bag comprising a hood having a hand hole with a flap closing the hole when the hood is upright and adapted to fall back when the hood is inverted, ribs radiating from the crown of the hood, and means for collapsing the hood and expell-ing the smoke through the hand hole when the hood is inverted, said means comprising braces attached to the ribs and a movable member connected to the braces and ar-ranged to be actuated externally of the crown.
4. A flashlight bag comprising a hood with a translucent screen covering the front and having a hand hole, a flap covering the hole when the hood is upright and falling back when the hood is inverted, ribs radi-ating from the crown, and means arranged to be pulled outwardly from the crown to collapse the ribs and hood, making room for the screen to fold in and automatically expel the smoke out of the hand hole, said means comprising braces attached to the ribs and an actuating shank connected to the braces.
5. A coupling between the standard and hood staff of a flashlight bag, comprising a bent bar with a standard fitting portion with means for keeping it from turning when fitted, a staff fitting portion inclined at a slight angle and non-circular to prevent turning, and an abutting shoulder at the bent place.
6. In a flashlight bag, a coupling for a

standard and hood staff, consisting of a one-piece bar bent to form portions at angles to each other, said portions being respec-tively insertible in the staff and standard in different positions to accordingly obtain dif-ferent degrees of inclination of the staff and hood, and a shoulder formed in the coupling at the juncture of the bends to abut the ends of the standard and staff.

7. In a flashlight bag, the combination of the shank, a brace collar affixed to one extremity of the shank, a rib supporting collar slidable back and forth on the shank in opening and closing the bag, and means disposed between said collars and encir-cling the shank to prevent the smoke reach-ing the shank and causing the sticking of the slidable collar.

8. In a flashlight bag, a hood including ribs, a shank, a brace collar affixed to one extremity of the shank, a grooved sleeve on the collar, a slidable collar on the shank providing a pivotal mounting for the ends of the ribs, a grooved sleeve on the slidable collar, and a flexible cover inclosing the shank between said sleeve and secured in the groove of said sleeve.

9. In a flashlight bag, a standard with a pin, a hood, a staff including two tubular members non-circular in cross section, a re-versible coupling having a non-circular por-tion fitting in the lower staff member, and a portion having a slot fitting over the pin in the standard, the upper portion of the staff being connected to the hood, and connect-ing means inside of the hood for the two-part staff, including a flash pan holder having non-circular stems fitting into the respective upper and lower staff portions.

10. In a flashlight bag, a hood having a hand hole, a flash pan holder situated at the base of the hand hole and provided with a peripheral groove to receive the cloth bounding the hand hole, the flash pan holder having an opening, a flash pan insertible in said opening and closing the opening when inserted, and means for holding the flash pan in position.

11. In a flashlight bag, a hood having a hand hole extending into the hood, a staff inside of the hood consisting of two parts, a flash pan holder having an opening in the middle with a peripheral groove to receive the fabric bounding the hand hole, stems carried by the flash pan holder inserted in the members of the staff, a flash pan retain-ing plate partly closing the opening and ex-tending from side to side, a flash pan being adapted to be inserted in the opening and extend beyond the opening at the side and beneath the edge of said retaining plate to completely close the opening, electrical con-tacts carried by the holder and the flash pan, said contacts establishing electrical communication when the flash pan is in

place, and a spring pressed trap door normally closing the flash pan holder opening but engaging the flash pan when in position to hold it in place.

- 5 12. A flashlight bag, comprising an inclined hood, a collar located in the crown of the hood, ribs radiating from the collar to support the hood and defining a rectangular front face, a staff inclined to the back 10 of the hood, of two parts, of which one is attached to the collar and the other reaches to a point in line with the lower ends of the bottom ribs; and a flash pan holder including oppositely extending 15 means on which the adjacent ends of the staff parts are fitted to couple the staff.

13. A flashlight bag comprising a hollow staff section, a stage connector plug secured to the staff section and having flexible wires leading through the hollow section 20 and terminating in a connector plug, and a proof light with a socket adapted to be fitted on the same connector, said socket wiping accumulations of dust on being fitted in position on the stage connector, to 25 insure clean contact.

GEORGE ALBERT LEY.
